UNITED STATES PATENT OFFICE.

JAMES H. BOYE, OF CHICAGO, ILLINOIS, ASSIGNOR TO THE BOYE NEEDLE COMPANY, OF CHICAGO, ILLINOIS, A CORPORATION OF ILLINOIS.

PENCIL-SHARPENER.

1,214,996.

Specification of Letters Patent.

Patented Feb. 6, 1917.

Original application filed October 20, 1915, Serial No. 56,924. Divided and this application filed March 31, 1916. Serial No. 87,933.

To all whom it may concern:

Be it known that I, JAMES H. BOYE, a citizen of the United States, residing at Chicago, in the county of Cook and State of Illinois, have invented new and useful Improvements in Pencil-Sharpener, of which the following is a specification.

This invention relates to lead pencil sharpeners of the character disclosed in my application No. 56,924, filed October 20, 1915.

The primary object of the present invention is to provide an improved device for sharpening the lead of the pencil after the wood has been pared.

The invention is illustrated in its preferred embodiment in the accompanying drawing, in which—

Figure 1 represents a perspective view of my improved lead-pencil-sharpener, the view showing a pencil undergoing the wood-paring operation; Fig. 2, a perspective view of the device, showing the opposite edge; Fig. 3, a perspective view of the device with the container partially open; Fig. 4, a sectional view taken as indicated at line 4 of Fig. 3; Fig. 5, a broken sectional view of the wood-paring device, shown removed from the casing, or container-holder, and illustrating the manner in which the wood is pared from the lead of the pencil; Fig. 6, a longitudinal vertical section taken as indicated at line 6 of Fig. 4, but showing the container-holder closed; and Fig. 7, a transverse section taken as indicated at line 7 of Fig. 4.

The invention, in its preferred embodiment, comprises a container-holder A; a combination pencil-guide and wood-paring device B, located in and carried by said container-holder; and a lead-abrader or abrasive lead-sharpening device, C, located in and carried by said container-holder.

The container-holder A, as the name implies, is adapted to serve as a container-holder for the elements B and C, and also as a container for the wood-parings and lead removed from the pencil in the sharpening operations. No claim is made in the present application, however, to the wood-paring device.

The container-holder A preferably comprises an open top box 1, and a slightly larger box-form closure, or cover, 2, which

receives the box 1 telescopically, the two members being connected near one end, by pivots 3.

The container-holder is preferably of the rectangular form shown, and may conveniently be made of a length of a couple of inches, and of a width of about one inch and a quarter. The box 1 has upturned narrow flanges, the lateral flanges being provided near the end distant from the pivots 3 with semi-circular recesses 1^a.

The cover 2 has downturned flanges of somewhat greater depth. The casing may be opened by pressing together the ends of the members 1 and 2, which project back of the pivots 3, thus separating the opposite ends of said members.

The device B comprises a pencil-guide 4 disposed between the lateral flanges of the cover 2 and equipped at its tapered portion with a sharpening blade 4^a. The device B is adapted to pare the wood of the pencil 5 without cutting the lead 5^a. The lead-pointing device C, in the form illustrated, comprises a pair of file-toothed, spring-held, jaws 6 and 7, which are disposed beneath or suspended from the top wall of the casing-member, or cover, 2. The file-members 6 and 7 have curved shank-portions securely fastened to the spring arms 8 of a member, or clip, 8^a, which has an attaching portion 8^b secured to the top wall of the casing-member 2, as by rivets 9^a. The spring-arms and the clip may be integrally formed; and the file-members may be secured to the spring-arms by having their shanks secured or confined between the bodies of the spring-arms and the members 8^b, which are struck from the arms by incising the metal and stamping the severed portion to the form desired. The file-members 6 and 7 are made concavo-convex, with their convex portions opposed to each other and the extremities separated, to afford between them a space 10, which registers with a hollow tapering guide-member 11 carried by one of the lateral flanges of the cover 2. The corresponding flange of the box 1 is recessed, as indicated at 1^b, to accommodate the guide-member 11.

After the pencil D has been inserted in the guide B, and turned therein to pare away the wood and leave the lead 5^a, the pencil is withdrawn from the device B, and the lead is then inserted through the guide 11, which

registers with a perforation 11^a in the lateral flange of the cover 2; and the lead is pointed by a reciprocating motion thereof between the spring-held file-members 6 and 7. The divergent end-portions of the file-members are preferably smooth, and the pointing of the lead is effected between the roughened convex portions. By the use of the opposed, spring-held file-members it is possible to secure a rapid sharpening operation by a simple longitudinal reciprocation of the pencil, accompanied by occasional slight rotary oscillation.

The fine shavings, or wood-parings, are deposited in the box, and the particles of lead removed by abrasion are received in the same chamber. In practice, the lead particles are sifted through and mixed with the parings, and there is sufficient affinity between the wood and lead particles to prevent the lead particles from sifting out through the openings of the casing.

On occasion, when it may be necessary, the container may be opened by pressing together the rear ends of the box-form members comprising the casing, thus permitting the contents to be dropped into a waste basket. The device may be freely handled, and the pencil-sharpening operation may be performed without soiling the hands.

The device described is simple, thoroughly effective, and may be cheaply manufactured.

The foregoing detailed description has been given for clearness of understanding only, and no unnecessary limitation should be understood therefrom.

What I regard as new, and desire to secure by Letters Patent, is—

1. A pencil sharpener comprising a container-holder having an opening in one wall and a registering guide projecting inwardly from said wall, and a pair of spring-held opposed file-members, located in said container-holder and having separated extremities disposed in alinement with said guide.

2. A pencil sharpener comprising a container-holder, a pair of spring-arms carried

thereby, a pair of opposed file-members confined between said spring-arms and having oppositely turned extremities affording a space between them, and a taper guide-member carried by one wall of said casing, and having its inner end in alinement with the space between said file-members.

3. A pencil sharpener comprising a container-holder having one wall provided with a perforation and equipped with a tapering guide, a pair of opposed file-members having diverging extremities affording between them a space in alinement with said guide, a pair of spring-arms carrying said file-members, and means securing said spring-arms to a wall of said container-holder.

4. A pencil sharpener comprising a holder, a pair of opposed file-members, spring-arms between which said file-members are confined, and a tapering pencil guide carried by said holder and disposed in alinement with the space between said file-members.

5. A sharpening device comprising a holder element, a pair of spring-arms carried thereby, a pair of file-members having opposed concavo-convex portions and diverging extremities, said file-members carried by said spring-arms and having smooth adjacent surfaces at their extremities, and a tapering pencil guide carried by said holder and disposed in alinement with the space between said file-members.

6. A sharpening device comprising a box, a cover pivotally united thereto, a clip secured to the inner side of said cover and carrying a pair of spring-arms, and a pair of file-members carried by said spring-arms and having opposed concavo-convex portions and diverging extremities, one flange of said cover having an opening in alinement with the space between said file-members.

JAMES H. BOYE.
